DESIGN FOR A CAMERA

Miller R. Hutchison, Jr., Rochester, N. Y., assignor to Eastman Kodak Company, Rochester, N. Y., a corporation of New Jersey

Application February 15, 1945, Serial No. 117,986

Term of patent 14 years

(Cl. D61—1)

To all whom it may concern:

Be it known that I, Miller R. Hutchison, Jr., a citizen of the United States, residing at Rochester, in the county of Monroe and State of New York, have invented a new, original, and ornamental Design for Camera, of which the following is a specification, reference being had to the accompanying drawing, forming a part thereof in which:

Fig. 1 is a perspective view of a camera showing my new design, this view being taken from the front and from a point slightly above and to one side of the camera.

Fig. 2 is a perspective view of the camera shown in Fig. 1 but taken from a point slightly above and to one side and from the back of the camera.

Fig. 3 is a fragmentary perspective view showing the bottom and parts of one side and the rear wall of the camera shown in the preceding figures.

I claim:

The ornamental design for a camera, as shown.
